[57] CLAIM

The ornamental design for a hanging fluorescent lighting fixture, as described and shown.

DESCRIPTION

FIG. 1 is a top, front perspective view of a hanging fluorescent lighting fixture showing my new design.

FIG. 2 is a top plan view on a reduced scale.

FIG. 3 is a side elevational view thereof on a reduced scale.

FIG. 4 is a cross-sectional view taken along line 4—4 of fixture 3.

FIG. 1

FIG. 4

FIG. 2

FIG. 3
